ELECTROMAGNETIC RELAY

James C. Hamilton, Lexington, Mass., assignor to
Combustion Control Corporation, Cambridge,
Mass., a corporation of Massachusetts

Application December 22, 1944, Serial No. 569,368

6 Claims. (Cl. 200—104)

1

This invention relates to electric switching apparatus and more particularly to electromagnetic relays.

It is the main object of the present invention to provide an electromagnetic relay which is especially suited for installation in equipment where absolute reliability, ruggedness, and compliance with various safety requirements and regulations are imperative.

Other objects of the invention are to provide a magnet relay having several sets of current-carrying conductors which are electrically and mechanically completely separated from each other and shielded in such a manner that they cannot be bridged by foreign objects or connected by air gaps that might promote arcing between contact elements of considerably different potential; to provide such relay apparatus which is composed of a minimum number of parts requiring a minimum amount of assembly operations, to provide a magnet relay which has completely separated, protected and especially sturdy main lead-in conductors, and similarly arranged switching elements; to provide such a relay which has very easily accessible terminals located conveniently on one side of the apparatus; to provide such a relay which has a practically unbroken contour within which are contained all moving enclosed elements, the assembly offering little opportunity for extraneous parts catching, or foreign particles collecting thereon; and generally to provide an electromagnetic relay of this type which is so organized that it includes the above-mentioned features with lowest possible expenditure of material and assembly work reconcilable with rugged and yet exact and safe construction.

These and other objects, aspects and features of the invention will be more fully apparent from the following description of a practical embodiment illustrating the genus of the invention. The description refers to drawings in which

Fig. 1 is a side elevation of an electromagnetic relay according to the invention, with open contacts;

Fig. 2 is a side elevation similar to Fig. 1, with the contacts closed;

Fig. 3 is a section on line 3—3 of Fig. 2, portions of which are shown in elevation;

Fig. 4 is a bottom view of the relay according to Figs. 1 and 2;

Fig. 5 is a section on line 5—5 of Fig. 3;

Fig. 6 is a section on line 6—6 of Fig. 2;

Fig. 7 is a section on line 7—7 of Fig. 3; and

Fig. 8 is a section on line 8—8 of Fig. 7.

In Figs. 1 to 7, numeral 1 indicates a base block made of insulating material. This block has essentially the form of a T, with face 2 that is flat excepting for the protective projections to be described hereinbelow, and suited for mounting the relay on a flat surface, for example plate 3

2

of an apparatus chassis or switchboard. The transverse portion 5 of block 1 extends over practically the entire width of the block (Figs 3 and 4) and carries imbedded therein a number of rigid contact bars 11, 12, 13, 14 and 15 (Fig. 3). These contact bars may be arranged in two groups belonging to different portions of a circuit and, if desired of different cross sections corresponding to different current-carrying requirements. 10 By way of example, contacts 11 and 12, which may have a comparatively high potential, are shown as somewhat heavier than conductors 13, 14 and 15 which may be of low voltage. The contact bars extend at both ends beyond portion 5 of block 1. The outer ends of the bars 11, 12 constituting one contact group are separated by a barrier 19 from bars 13, 14, 15 constituting a second group. The inner ends of the bars are similarly separated by a barrier 20 in the usual manner provided with contact points of suitable material.

The block 1 may consist of any suitable insulating material with the contact bars fixed therein in appropriate fashion, but I prefer to imbed these bars into the block while the latter is molded according to the method set forth in my copending application Serial No. 582,914, filed March 15, 1945, now abandoned.

The longitudinal portion of block 1 is provided 30 with openings 118, 119 (Figs. 4, 6) for wires leading to the magnet coil 40 (Figs. 1, 2, 6). If the mounting element 3 consists of insulating material, such openings will often be satisfactory. In other instances however, for example if plate 3 35 is made of metal, it may be preferable to provide bosses 21, 22 containing, preferably moulded thereinto, magnet coil leads 23, 24, which extend on both sides beyond the bosses and have the purpose of carrying current to the magnet coil 40 of the relay. These bosses may be integral with block 1 or, as indicated in Fig. 6 they may be formed separately with threads for screwing them into corresponding threads of openings 118, 119.

45 The base block 1 has a corner portion 26 which locates one leg of the core structure 31 which is provided with three legs 32, 33, 34. Leg 32 has punched thereinto two openings 28, 29 corresponding to openings 18, 19 which may be provided with bosses 21 and 22, as indicated in Figs. 4 and 6. Leg 32 also serves for fastening the magnet core structure to block 1, by means of screws 35 and 36 (Fig. 4) which may be staggered with respect to openings 118, 119. A mounting 50 screw 38 is firmly inserted into a tapped hole 39 of core leg 32 and has an extension projecting in the direction of bars 11 to 15, for the purpose of receiving a nut (not shown) by means of which the relay can be firmly fastened to the mounting element 3.

The magnetic core leg 33 carries in conventional manner a magnet coil 40, the ends of which may lead through openings 118, 119 or are connected, as by soldering, to the ends 41, 42 of magnet coil leads 23, 24 as shown in Fig. 1.

The third leg 34 is provided with two brackets 51, 52 which extend inwardly and have holes 54, 55, which are adapted to receive a hinge pin 59 fastened thereto in the manner to be described below.

The magnetic circuit is completed by armature iron 70 which is secured, by means of two screws 73, 74 (Figs. 7, 8) to an armature block 80 now to be described.

The armature block consists of two portions both of insulating material, namely a carrier plate 81 and a cover plate 82 (Figs. 1, 5, 7, 8). The cover plate 82 is provided with two bosses 83, 84 (Figs. 3, 7) which fit into somewhat larger, corresponding recesses 85, 86 (Fig. 8) of carrier plate 81. These recesses are at their openings surrounded by somewhat wider, flat and shallow recesses 87, 88 (Figs. 3, 7) which are open on the side toward the contact bars 11 to 15 and correspond to widened portions at the base of bosses 83, 84 of cover plate 82. Carrier plate as well as cover plate have two holes through the center of bosses 83, 84 and through plate 81 below the recesses 85, 86, respectively, for screws 73, 74 mentioned above, which screws join the two portions of the armature block to each other and to armature iron 70. Cover plate 82 has appropriate recesses for the sunk heads of screws 73 and 74.

The cover plate 82 is provided with a dividing barrier 100 (Figs. 1, 3, 5, 8) which is integral therewith and which fits into a groove 101 of carrier plate 81. This dividing barrier extends into the space between the fixed contact bar groups mounted on block 1 and provides with the above-mentioned barrier 20 of block 1 (Figs. 1, 3, 7) two securely separated chambers for the two sets of contacts. It will be evident that barrier 100 is not necessarily integral with cover plate 82 but may be integral with carrier plate 81 and fit into a groove of plate 82; the barrier 100 may also be formed as a separate piece suitably fitted and secured to plates 81 and 82.

The armature block contains two sets of contact springs 92, 93 (Figs. 3, 7, 8), with bridge portions 95, 96 that fit into recesses 87, 88, and have holes that fit around bosses 83, 84. It will be evident that, with screws 73, 74 properly tightened, the contact springs 92, 93 are firmly fixed to the armature block, these screws at the same time firmly joining the two portions of the armature block to the armature iron 70.

The contact springs 92, 93 have contact prongs 111, 112, 113, 114, 115, which extend beyond the ends of bars 11 to 15 and are, similar to the latter, provided with appropriate contact points.

The carrier block 81 is further provided with a lifting ridge 120 upon which contact springs 111 to 115 rest when the armature block 80 is tilted away from the magnet, whereas the springs leave the lifting ridge upon making contact with the contact bars 11 to 15. It will be evident that, due to the resiliency of contact springs 111 to 115, these springs will, with the armature block tilted, rest firmly against the ridge 120, which thus keeps them in proper alignment and assures simultaneous contacting at all points. Contact springs 92 and 93 may of course have any number of prongs, depending upon the desired number of contact points.

As mentioned above, the separating barrier 75

100 of cover plate 82 extends beyond the ends of contact prongs 111 to 115 and overlaps with barrier 20 of base block 1. In this manner the two groups of contacts, namely 11, 12 and 111, 112, and 13 to 15 and 113 to 115, are effectively separated from each other, for mechanical as well as electrical purposes. It will be evident that more than two contact groups can be effectively separated in this manner, if desired.

10 The outer edge 135 (Figs. 1, 5, 7) of cover plate 82 corresponds to an angular recess 126 of base plate 1. This provides for an effective closure between base block 1 and block 80 especially when the contacts are closed, but even in "open" position of the armature as shown in Fig. 1. The outer end 135 of carrier plate 81 and armature iron 70 extends beyond transverse portion 8 of base block 1 and constitutes an insulating barrier between the armature metal and the contacts, and it also provides a stop for the armature.

15 The armature iron 70 has two lugs 154, 155 corresponding to brackets 54, 55 of the core, as above described. The hinge pin 59 (Figs. 5, 6) may be inserted into a groove 156 of plate 70, in order properly to locate the pivot point with respect to the plane of contact of plate 70 and magnet core 33. The hinge pin fits loosely in lugs 154, 155 but is fixed in brackets 54, 55 by expanding it within holes 54, 55, as indicated by the 20 marks shown in Fig. 6.

25 The armature iron 70 is also provided with one semicircular and one circular cut-out, clearly indicated in Fig. 6, and adapted to receive one fastening hook 57 of spring 58, whose other end 30 is hooked to a screw eye 61, fastened to the core 31. The armature iron 70 also has two tapped holes 71, 72 adapted to receive bolts 73, 74 as above described.

35 It will be evident that the lateral openings of the armature block 80 may be provided with closing walls similar to center barrier 100. In cases where it is justified to retain the contacts fully enclosed, these outer walls provide complete protection of the switching elements.

40 Instead of using the tension spring herein shown a compression spring of metal or rubber may be used, in which case the pivot will be suitably placed in conformity with the action of the spring.

45 This relay operates as follows.

50 Coil conductors 23 and 24 having been connected to an energizing relay circuit, and the terminals of contact bars 11 to 15 to the appropriate circuit elements of apparatus to be controlled by the relay, the contact points of 11 to 15, and 111 to 115 will remain separated so long as the magnet is deenergized. Upon energization of coil 40, armature iron 70 is attracted by magnet core 33, and the spring contacts 111 and 115, having been 55 lifted from ridge 120, conductively connect conductor wires 11 and 12, and 13 to 15, respectively, making circuit between the wires connected to the contact bars.

60 When the current supply to the coil 40 is interrupted, spring 58 lifts the armature block, ridge 120 disconnects the contact springs 111 to 115 from the corresponding rigid contact bars 11 to 15 until the end portion 135 of plate 81 contacts block portion 8, and the respective circuits are 65 interrupted.

70 It will be noted that the contact points are 70 protected against disturbing frontal interference in open as well as in closed position, as shown in Figs. 1 and 2, respectively. It will further be noted that the present construction permits sepa-

ration of all lead wires from the relay proper, on the other side of the mounting plate 3, and easy accessibility of the lead connections.

It should be understood that the present disclosure is for the purpose of illustration only and that this invention includes all modifications and equivalents which fall within the scope of the appended claims.

I claim:

1. In an electromagnetic relay of the type having a magnetic core structure associated with an energizing coil, and an armature structure including a magnetic armature member movably secured to the core structure, the combination of a solid insulating base block fastened to said core structure, and to which are rigidly fastened two sets of substantially stationary and rigid contact bars freely extending beyond a face of said block, and carrying on said face a barrier extending toward the ends of, and separating said contact sets; an insulating base plate secured to said armature member, and carrying two sets of contact springs constructed and arranged with freely extending ends to bridge at least two of said contact bars; and a cover plate secured to said base plate, one of said plates having a groove between said contact springs and the other plate having a barrier which extends into said groove and also projects between said contact springs and said contact bar sets so as to overlap said base block barrier.

2. In an electromagnetic relay of the type having a magnetic core structure, a coil associated with the core structure, and an armature structure movably secured to the core structure and including a magnetic armature member, the combination of an insulating base block which is fastened to said core structure and which contains rigidly fastened thereto two sets of substantially stationary and rigid contact bars, with an armature block including an insulating base plate secured on one side to said magnetic armature member, a cover plate secured to the other side of said base plate, and two resilient contact means free from external electrical connections and each arranged to bridge at least two of said contact bars and secured between said base plate and said cover plate, one of said plates having a groove between said resilient contact means and the other plate having a barrier extending into said groove and between said contact means and said contact bar sets, and said base plate and said cover plate extending over said contact means and said sets, thereby separating said two sets and their corresponding contact means.

3. In an electromagnetic relay of the type having a magnetic core structure, with which an energizing coil is associated, and to which a magnetic armature is movably secured, the combination of an insulating T-shaped base block, the longitudinal portion of which is fastened to said core structure and the transverse portion of which has fixed thereto substantially rigid contact bars, with an armature block including an insulating base plate secured on one side to said magnetic armature member, a cover plate secured to the other side of said base plate, and two resilient contact means free from external electrical connections and each arranged to bridge at least two of said contact bars and secured between said base plate and said core plate; one of said plates having a groove between said resilient contact

means; and the other plate having a barrier extending into said groove and between said contact means and said contact bar sets, said base plate and said cover plate extending over said contact means and said sets, thereby separating said two sets and their corresponding contact means.

4. A combination according to claim 3 wherein either of said resilient contact means comprises a plurality of leaf springs joined together at one end.

5. In an electromagnetic relay of the type having a magnetic core structure, with which an energizing coil is associated, and to which a magnetic armature is movably secured, the combination of an insulating T-shaped base block, the longitudinal portion of which is fastened to said core structure and the transverse portion of which has integrally molded therein substantially stationary and rigid contact bars both ends of which extend from said transverse portion, said longitudinal portion containing conductors adapted to lead to said coil and extending transversely through said core structure; an armature block including a base plate secured on one side to said magnetic armature member, a cover plate secured to the other side of said base plate, and two resilient contact means free from external electrical connections and each arranged to bridge at least two of said contact bars and secured between said base plate and said cover plate, one of said plates having a groove between said resilient contact means and the other plate having a barrier extending into said groove and between said contact means and said contact bar sets, said base plate and said cover plate extending over said contact means and said sets, thereby separating said two sets and their corresponding contact means.

6. In an electromagnetic relay of the type having a magnetic core structure, with which an energizing coil is associated, and to which a magnetic armature is movably secured, the combination of an insulating T-shaped base block, the longitudinal portion of which is fastened to said core structure and the transverse portion of which has fixed thereto substantially rigid contact bars, and carries a projecting barrier between said bars, with an armature block including an insulating base plate secured on one side to said magnetic armature member, a cover plate secured to the other side of said base plate, and two resilient contact means each arranged to bridge at least two of said contact bars and secured between said base plate and said core plate; one of said plates having a groove between said resilient contact means; and the other plate having a barrier extending into said groove and between said contact means and said contact bar sets, and overlapping the barrier on said base block.
